UNITED STATES PATENT OFFICE.

JESSE COLLINS KANE, OF EASTON, PENNSYLVANIA, ASSIGNOR TO CHIPMAN KNITTING MILLS, OF EASTON, PENNSYLVANIA, A CORPORATION OF PENNSYLVANIA.

KNITTING MACHINE.

Application filed April 5, 1923. Serial No. 629,970.

To all whom it may concern:

Be it known that J. JESSE C. KANE, a citizen of the United States, residing at Easton, in the county of Northampton and State of Pennsylvania, have invented certain new and useful Improvements in Knitting Machines, of which the following is a specification, reference being had to the accompanying drawings.

- 10 My invention relates to knitting machines, more specifically to knitting machines of the rotary or circular type adapted primarily for production of tubular fabrics.
- 15 The paramount object of my invention is to enable knitting upon such a machine, tubular stocking blanks having flat, integral prolongations or extensions with parallel side edges, such as employed for example in the method of stocking manufacture described in connection with appropriate illustrations in Patent No. 923,605 granted to Albert Gee under date of June 8, 1909. This patent explains how a stocking blank of the desired form may be produced upon 20 25 30 35 40 45 50 55 60 65 70 75 80 85 90 95 100 105 110 a circular knitting machine by oscillatory or reciprocatory knitting by use of a selected group of needles, but difficulty has heretofore been experienced in securing perfect selvages along the parallel side edges of the prolongations or extensions aforesaid. This difficulty I have found to be due to crowding of selvage loops formed as a result of the constant functioning of the end or terminal needles of the active needle group. Owing to such crowding, the selvages were characterized by looseness so that the ends of the web invariably became displaced from beneath the retaining notches of the contiguous web holders with the result that, in the course of the subsequent rise of the terminal or end needles, said needles would puncture adjoining portions of the web previously knitted. This obviously caused either the formation of tuck stitches or latch closure and therefore undesirable irregularities and imperfections in the knitting which subsequently prevented proper looping of the fabric in applying the same to other machines for the purpose of appending a fashioned foot. By the present invention I am enabled to avoid any fabric imperfections whatsoever, and this is accomplished by so controlling the operation of the end or terminal needles 55 of the group producing the elongation or

extension of the stocking blank, that they function only in production of alternate courses of the knitting. In this way not only is the possibility of looseness in the selvage loops positively precluded, but an even distribution and uniform tensioning of said loops, with respect to the other loops of the fabric, obtained. Furthermore, the selvages thus produced, present the appearance of a perfect finish, and lead themselves readily to "boning" (loop dilation) preparatory to transfer.

Other subsidiary objects, together with their attendant advantages, will become readily apparent from the detailed description which follows of a typical embodiment of this invention. The scope of my invention as at present known to me will, in turn, be as readily apparent from the appended claims.

In the drawings, Fig. I is a side elevation of a knitting machine conveniently embodying my invention, certain parts not pertinent to the present purpose being either omitted or broken away.

Fig. II is an axial sectional view on an enlarged scale of the needle cylinder, its support and various adjuncts, the plane of section being as indicated by the arrows II-II in Fig. I.

Fig. III is a detail plan view of the bed by which the needle cylinder is supported showing the knitting cams, pickers and other instrumentalities designed to control actuation of the needles.

Figs. IV and V are linear developments of the needle actuating cams illustrating the pickers in the performance of special functions which I allot them.

Fig. VI is a diagrammatic illustration of a stocking blank produced in accordance with my invention; and

Fig. VII is a conventional illustration of the characteristic type of selvage edge produced on my improved machine; and

Fig. VIII is a fragmentary view illustrating the different length needle butts hereinafter more particularly referred to.

The machine which I have chosen for the purposes of illustration herein, is of a type exemplified in Patent No. 1,152,850 granted under date of September 7, 1915, to R. W. Scott, and comprising with reference more particularly to Fig. I of the drawings, a needle cylinder designated by the numeral 1

which is rotatably supported in an overhang extension 2 of a bed plate 3 forming the top member of the housing frame 4 of the machine. Motion is imparted to the needle cylinder 1 through the medium of a bevel gear 5 coordinated with an intermeshing bevel gear 5^a (Fig. II), secured upon the inner end of the main or driving shaft 6, the latter being journalled in suitable bearings 7-7 of the housing frame 4. Upon the shaft 6 are mounted pulleys 8-8 for belt connection with an appropriate source of power, also a shiftable clutch collar 9 adapted to be engaged either with a gear pinion 10 or a pinion 11 for determining rotary or reciprocatory drive of the needle cylinder 1 through interposed instrumentalities which are clearly described in the patent referred to and need not therefore be further set forth in detail herein. The clutch collar 9, it will be noted, is circumferentially grooved for engagement by a shipper arm 12 fixed to a horizontal rod 13 supported for longitudinal movement in guides 14-14 of the housing frame 4. The movement of the shipper arm 12 is controlled by a rotary cam drum 15 forming one of the elements of the pattern mechanism of the machine, and mounted for independent rotation upon a counter shaft 16. Attention is specially directed to the fact that the cam drum 15, instead of having two off sets or deviations in its circumferential cam groove 17, (as ordinarily provided in seamless stocking knitters for shifting the clutch for heel and toe pocket knitting), has but a single one indicated at 18 for a reason which will be later explained. A ratchet wheel 19 is provided for intermittent progression of the drum 15, pawling of said ratchet being subject to control of suitable high links (not shown) on a pattern chain 20 in a well known way.

Attention is now directed to Fig. II of the drawings, wherein it will be observed that the knitting needles comprehensively indicated by the numeral 21, are retained for vertical movement in guide grooves of the cylinder 1, and have associated with them the usual web holders 22. These web holders 22 are appropriately supported for horizontal sliding toward and away from the needles 21 in a head 23 secured about the top of the needle cylinder 1, and are moved back and forth in the well known manner by suitable cams in said head. The cams whereby the needles 21 are actuated include, as best shown Fig. III and also in the dia-grammatic illustrations of Figs. IV and V, a stitch forming group indicated by the numeral 25, and a switch cam 26. The needles 21 which up to this time have been referred to only in general, really comprise two groups, (Figs. IV and V) a long butt series 27 (indicated conventionally in heavy lines)

and a complementary short butt series 28 (indicated in light lines), the two series being equal or nearly so as to number. The long butt (heavy shaded) series 27 are, by proper positioning of the switch cam 26 coincidentally with the change of drive of the machine from rotary to oscillatory or reciprocatory knitting, raised to the idle level when knitting is to be effected only upon the short butt series 28, one way in which the described action of the switch cam 26 and also subsequent repositioning of the same to lower said long butt needles 27 when round and round knitting is to be resumed, is readily ascertainable from the Scott patent to which attention has been directed. In addition to the cams 25, 26 thus far described, the needle actuating means further includes the usual pair of elevating pickers 30, 30^a which are coupled by means of a connecting link 31 (Fig. III) so that one is brought to needle butt engaging position during the activity of the other, and also a drop picker 32 whose lateral overhang projections, it will be particularly noted, of an extent to engage only a single needle butt at a time instead of two as ordinarily provided for in standard knitting machines. As a result of this arrangement, activity of the pickers will be confined wholly to the terminal needles 28^a and 28^b of the short butt series 28. The needle 28^a, characterized by cross hatching in Figs. IV and V of the drawings, which, although included in the short butt series 28, has a medium length butt as best shown by Fig. VIII so as to be raised initially by the switch cam 26 to the idle level with the long butt series 27 in readiness to be engaged by the drop picker 32 upon the first reverse movement of oscillation or reciprocation of the machine. These terminal needles 28^a and 28^b, which for convenience of nomenclature and better distinction will, in further description and claims be referred to as special or supplemental end needles, are therefore constantly projected and retracted incidentally to the activity of the short butt series 28.

The machine is preferably further equipped (see Fig. I) with a standard form of welting dial 34 useful in the production of welt tops with which ladies' hose are ordinarily provided. This dial 34 is rotated in unison with the needle cylinder 1 by gear connections concealed within a guard 35 and coordinated with a vertical shaft 36 which in turn receives motion from the main drive shaft 6 through the medium of an interposed bevel gear couple 37. Referring again to Fig. II it will be observed that the needle cylinder 1 is provided with jacks 38 which are disposed in the guide grooves with alternate needles 21 and have butts adapted to follow a cam groove 39 located subjacent to the knitting cams 25. This

cam groove 39 is plainly shown in Figs. IV and V, but in order to avoid confusion the jacks 38 have been omitted from these illustrations. The jacks 38 by engaging alternate needles 21 from beneath, and through motion induced by the cam groove 39, elevate them above the usual or normal path followed by the other needles. Subdivision thus effected makes possible the starting of a perfect web upon bare needles and is also important in connection with the operation of the welting dial 24 after the manner set forth in the patent aforementioned.

Yarn is directed to the needles by interchangeable feeds 40 mounted to swing upon a common fulcrum shaft 41 which is appropriately anchored in upstanding lugs 42 of the latch guard ring 43. These feeds 40 are controlled through interposed thrust bars 44, from a cam drum 45 (Fig. I) which is intermittently rotated by virtue of gear connections 46 with the pattern drum shaft 16 already described.

The operation of the machine, with reference to the stocking blank produced by it shown diagrammatically in Fig. VI of the drawings, is as follows:

In this illustration the welt top indicated at 50 is knit with the aid of the welting dial 34 in the manner described in the Scott patent supra, round and round knitting being continued thereafter beyond the line 51 of the welt juncture to produce the leg portion 52 of the blank, which portion may be of any length as predetermined by the pattern chain 20. At the completion of the leg portion 52 along the course 53, a change is made in the drive of the machine from rotation to reciprocation through shifting of the clutch collar 9 from the gear pinion 10 to the pinion 11 under action of the offset 18 in the groove 17 of the pattern drum 15. During the final round or rotation of the machine, the switch cam 26 is automatically swung, by well known means provided for the purpose, to an inclined position to elevate the long butt needles 27 together with the special medium butt end needle 28^a to the upper or idle level shown in Fig. IV, said long butt needles holding their loops throughout the reciprocatory knitting which follows, whereby a flat integral prolongation or extension 54 is added to the blank. Immediately upon the first reverse movement of reciprocation suggested by the large arrow in the figure last referred to, the special medium butt needle 28^a is engaged by the drop picker 32 and depressed to the active level. The special needle 28^a consequently follows the active needle path with the short butt needle 28, (which path is indicated by the smaller arrows in Fig. IV), and makes a terminal selvage stitch along the edge 55 of the prolongation 54. However, upon reciprocatory movement of the

needle cylinder 1 in the opposite direction as in Fig. V, the special needle 28^a engages the elevating picker 30^a whereby it is raised and restored to the inactive level so as to be beyond the scope of the knitting cams 25 during the current reciprocation. As a consequence of the behavior of the special needle 28^a, a stitch is made by the same only at the end of each alternate oscillation, such stitches being indicated at "S" in Fig. VII of the drawings. Similar reasoning will show that the special needle 28^b follows an identical rule of action and functions during the idle periods of the special needle 28^a in forming the terminal loops in the selvage edge 56 at the opposite side of the prolongation 54. It will therefore be seen that by reason of intermittent functioning of the special end needles 28^a and 28^b, loop crowding along the selvages cannot possibly take place thereby insuring that the ends of the fabric are engaged by the nibs of the web holders with consequent avoidance of the imperfections hereinbefore pointed out as attending the constant functioning of the end needles. After the desired length of the selvaged flat web 54 has been knit, the fabric is "pressed off" as a result of automatic restoration of the machine to its rotative phase and incidental retraction of the yarn feeds 40 to inactive position. In the course of its knitting, the stocking blank may have a line of demarcation 57 produced upon it extending longitudinally of the tubular portion and centrally through the prolongation 54. Such a line is useful as a guide for subsequent seaming or for ornamental purposes, and may be produced either by omission of a needle or by tucking. A similar line of demarcation 58 for facilitation of looping, may be made transversely of the end of the prolongation 54, for example, by knitting a course of loose or elongated loops.

Although I have herein relegated to the pickers 32 the office of controlling the action of the special end needles 28^a and 28^b, it is of course to be understood that any other means suitable to the purpose may be employed instead of said pickers without departing from the scope of my invention.

Having thus described my invention, I claim:

1. In a circular knitting machine, the combination with a series of needles for knitting a flat web, of medium-butt end needles, and means for actuating the same intermittently to produce selvage loops in alternate courses along opposite side edges of the web.
2. In a circular knitting machine, the combination with a selected group of needles for knitting a flat web, of medium-butt terminal needles, and means for actuating the same in respective alternation to pro-

- duce selvage loops at opposite sides of the web.
3. In a circular knitting machine, the combination with a selected group of short butt needles for knitting a flat web, of medium-butt end needles, and means for actuating the same at intervals to produce selvage loops in respective alternation at opposite sides of the web.
- 10 4. In a circular knitting machine, the combination with a grouped series of needles for knitting a flat web, of medium-butt supplemental end needles for said series, and pickers intermittently operative upon the medium butt needles at intervals to assist formation of complete selvage loops along opposite side edges of the web.
- 20 5. In a circular knitting machine, the combination with a selection of short-butt needles for knitting a flat web, of supplemental medium-butt end needles therefor, and pickers intermittently operative upon the medium-butt end needles to assist formation of complete selvage loops at intervals on opposite side edges of the web, said pickers including a drop picker with but sufficient projecting overhang to engage the medium-butt end needles.
- 30 6. In a knitting machine, the combination with a series of needles for knitting a flat web and including medium-butt supplemental end needles, of stitch cams for actuating said needles, and pickers operative upon the
- medium-butt end needles of the series only to move the same into and out of the province of the stitch cams for the purpose of producing selvages along opposite side edges of the web.
7. In a circular knitting machine, the combination of a series of needles adapted to produce tubular knitting, means for effecting subdivision of said needles to render a certain group inactive during production of a flat prolongation of the tubular knitting aforesaid on the remaining needles, and means for actuating medium-butt end needles in the series intermittently to produce selvage loops alternatingly along opposite side edges of the flat prolongation.
8. A circular series of needles including a short butt group and a long butt group with special medium-butt needles interposed between said short and long butt groups, means operative upon the long and medium-butt needles to shift them to inactivity during reciprocatory knitting with the short butt needles alone, and means for incidentally actuating the special medium-butt needles to assist formation of selvage loops in alternate courses respectively in the side edges of a flat web produced by oscillatory knitting with the short butt needles.

In testimony whereof, I have hereunto signed my name at Easton, Pennsylvania this 25th day of March 1923.

JESSE COLLINS KANE.
